LUG STRAP HOLDER FOR PICKER STICKS

Harrison L. Williams, Huntsville, Ala.

Application May 19, 1944, Serial No. 536,373

1 Claim. (Cl. 139—154)

This invention relates to looms and more particularly to an improved picker stick lug strap holder which is engaged by the operating lug strap for the picker stick.

An object of this invention is to provide an improved wedge-shaped lug strap holder having a head at its upper end which is clamped to one side of the picker stick and is engaged by the operating lug strap which actuates the picker stick.

Another object of this invention is to provide a wooden lug strap holder which is formed at its inner side with serrations engageable with one edge of the picker stick, the serrations gripping with the picker stick so that the lug strap holder will not move lengthwise of the picker stick.

A further object of this invention is to provide a lug strap holder of this kind which can be easily and cheaply constructed and will provide a long wearing lug strap holder.

With the foregoing and other objects in view, the invention will be more fully described hereinafter, and will be more particularly pointed out in the claim appended hereto.

In the drawing wherein like symbols refer to like or corresponding parts throughout the views,

Figure 1 is a detailed side elevation of a lug strap holder constructed according to an embodiment of this invention, mounted on a picker stick, the picker stick lug being broken away.

Figure 2 is a perspective view of the lug holder or holder, and

Figure 3 is a rear elevation of the lug strap holder.

Referring to the drawing, the numeral 10 designates generally a rockable picker stick which forms part of a conventional loom construction, and is adapted to be rocked by means of a lug strap 11 connected to the picker stick 10 at a point upwardly from the fulcrum or lower end thereof.

The picker stick 10 has positioned on the outer side or edge thereof, a wedge-shaped lug strap holder 12, about which the lug strap 11 engages. The lug strap holder 12 is clamped to the picker stick 10 by means of a U-shaped clamp 13 which also engages over a pressure plate 14, positioned on the outer edge of the lug strap holder 12. The lug strap holder 12 includes an elongated body having a flat side 15 engageable against the adjacent edge of the stick 10, and the side 15 is formed at a point extending upwardly from the lower end thereof with a plurality of serrations

16. The serrations 16 extend from the flat side 15 so that when the clamp 13 is tightened, the serrations 16 will bite into the adjacent edge of the stick 10. The lug strap holder 12 also includes a downwardly and inwardly inclined outer side 17 forming a wedge-shaped lug strap holder, and the outer side 17 terminates at a point below the upper end of the lug strap holder 12. An outwardly projecting head 18 is formed 10 above the upper end of the outer side 17 so that the upper edge of the lug strap 11 will be held against upward movement during the rocking of the picker stick. The upper edge of the head 18 is inclined downwardly and outwardly as indicated at 19.

In the use of this device, the lug strap holder 12 is clamped to the outer edge of the picker stick 10 by means of the U-shaped clamp 13 which engages over the pressure plate 14. The upper end 20 of the plate 14 comprises a stop for the lug strap 11 to limit the downward movement of the lug strap on the lug strap holder 12, whereas the head 18 constitutes an upper stop for limiting the upward movement of the lug strap 25 on the lug strap holder. By providing a lug strap holder with the projecting serrations 16, the tightening of the clamp 13 will project the serrations 16 into the adjacent face of the stick 10 so that the lug stop holder 12 will thereby be held firmly against lengthwise or vertical movement with respect to the picker stick. This lug strap holder can be manufactured at small cost so that it can be readily replaced when it becomes worn by the lug strap 11. However, due to the improved construction of the lug strap holder it will last for a longer period of time than lug strap holders heretofore in use, and will not become loosened on the picker stick as readily as will lug strap holders which do not embody the teeth or serrations 16.

What is claimed is:

A picker stick lug strap holder comprising an elongated member of substantially wedge shape and adapted to engage against one side of the picker stick, said member having a head at the large end thereof, and serrations formed on and offset from the edge of said member confronting said picker stick, said serrations being positioned adjacent the small end of said member and terminating at a point adjacent the lower edge of the area engaged by said strap.
